UNITED STATES PATENT OFFICE.

RICHARD F. DOWNEY, OF MILWAUKEE, WISCONSIN, ASSIGNOR TO THE AUTOMATIC PORTABLE BOWLING ALLEY COMPANY, OF MENOMINEE, MICHIGAN.

HAND-BALL.

SPECIFICATION forming part of Letters Patent No. 700,411, dated May 20, 1902.

Application filed August 17, 1901. Serial No. 72,380. (No model.)

To all whom it may concern:

Be it known that I, RICHARD F. DOWNEY, a citizen of the United States, and a resident of Milwaukee, in the county of Milwaukee, 5 and State of Wisconsin, have invented certain new and useful Improvements in Hand-Balls; and I do hereby declare that the following is a full, clear, and exact description thereof.

My invention relates especially to balls employed in bowling-alleys; and it consists in certain peculiarities of construction and combination of parts, as will be fully set forth hereinafter in connection with the accompanying drawings and subsequently claimed.

15 In the said drawings, Figure 1 is a view of one of my improved balls, partly broken away and in section on the line 1 1 of Fig. 3 to better illustrate certain details of construction. Fig. 2 is a like view, but with the ball 20 disposed at right angles to the position shown in Fig. 1 and with the interior parts shown as they appear looking from the line 2 2 of said Fig. 1. Fig. 3 is a like view, partly in section, on the line 3 3 of Fig. 1; and Fig. 4 is a 25 detail sectional view on the line 4 4 of Fig. 1.

Heretofore with the ordinary balls employed in bowling the same, particularly those of large diameter, have been usually made with finger and thumb holes bored 30 therein for the more ready handling of the balls, and as a result it is seldom that such balls will roll in a straight line from one end of the alley to the other. My present invention is designed to obviate this defect by 35 means of the construction herein illustrated and described.

Referring to the drawings, *a* represents a ball of ordinary material employed in bowling, said ball having a section or portion 40 thereof cut out, as indicated in the drawings, within which recess thus formed there is secured a casing consisting, primarily, of two metallic or other plates *b c*, the plate *c* having a laterally-projecting base portion *d*, 45 whereby the two plates are fastened together, as by a screw or rivet *e*. Between the said plates there are secured by the pivots *f f* a pair of spring-controlled movable plugs *g h*,

the shanks of said plugs being shouldered or offset, as best shown in Fig. 4, after the manner of shear-blades, and there being a pair of springs *i i* secured to the base-plate *d*, the free ends of said springs bearing against the lower free edges of said plugs to keep their outer ends normally spread apart to their fullest extent, as shown in Fig. 1, the outer edges of the plates *b c* being united and centrally closed, as by the stationary block *j*, secured in place, as by a screw *k* or otherwise, the inner surface of this block *j* being concaved from each end toward its center, so as to just permit the heads of the plugs *g h* to pass under the same when said heads are forced together by the thumb and finger of the person using the ball, the latter being very slightly cut away, as shown at *m m*, to just receive the finger and thumb nails of the one grasping the ball at the beginning of the contact. The opposite side edges of the plugs *g h* are further preferably slightly recessed, as indicated at *n n*, to afford a better thumb-and-finger grasp when those members are thrust into the ball, and the plugs are preferably bored partly through and fitted with springs *o* and pins *p* and the adjacent plate indented to receive the said pins, thus affording a slight momentary detent for the plugs in a partly-compressed position, thereby facilitating the entrance of the thumb and finger to the full extent and lessening the frictional contact of the plugs therewith in the beginning.

The operation of my device will be apparent from the foregoing description of its construction, taken in connection with the accompanying drawings, and in use the moment 85 the ball leaves the hand of the player the springs *i i* will force the plugs to the full-closed position shown in Fig. 1, thereby insuring that the ball is better balanced than if the thumb and finger holes were left open 90 and aiding said ball in keeping a straight course on the alley, the exterior contour of the plugs *g h* then conforming exactly to the outer shape of the ball and completing the sphere.

Having thus described my invention, what

I claim as new, and desire to secure by Letters Patent, is—

A hand-ball, recessed for the reception of the thumb and finger of the user, in combination with pivoted spring-controlled plugs for closing the same.

In testimony that I claim the foregoing I

have hereunto set my hand, at Milwaukee, in the county of Milwaukee and State of Wisconsin, in the presence of two witnesses.

RICHARD F. DOWNEY.
